attorney.

UNITED STATES PATENT OFFICE.

WALTER HENRY CLARKE, OF TORONTO, ONTARIO, CANADA.

DESIGN FOR A RUBBER HEEL.

59,714.

Specification for Design.

Patented Nov. 22, 1921.

Application filed June 1, 1921. Serial No. 474,259. Term of patent 14 years.

To all whom it may concern:

Be it known that I, WALTER HENRY CLARKE, a citizen of the United States, residing at the city of Toronto, in the county of York and Province of Ontario, Dominion of Canada, have invented a new, original, and ornamental Design for Rubber Heels, of which the following is a specification, refer-

ence being had to the accompanying drawing, forming part thereof.

The figure is a plan view of the rubber heel showing my new design.

I claim:

The ornamental design for a rubber heel as shown.

WALTER HENRY CLARKE.
